UNITED STATES PATENT OFFICE.

BELLVILLE L. RANDALL, OF BOSTON, MASSACHUSETTS.

CAR-BRAKE.

SPECIFICATION forming part of Letters Patent No. 337,616, dated March 9, 1886.

Application filed October 24, 1885. Serial No. 180,872. (No model.)

To all whom it may concern:

Be it known that I, BELLVILLE L. RANDALL, a citizen of the United States, residing at Boston, in the county of Suffolk and State 5 of Massachusetts, have invented a new and useful Improvement in Car-Brakes, of which the following is a specification, reference being had to the accompanying drawings.

My invention relates to that class of car- 10 brakes in which two brake-beams carrying the brake-shoes are swung simultaneously by means of a lever pivoted between the places of connecting the same by rods with said beams, and in which provision is also made 15 for equalizing the pressure of the brake-shoes upon the car-wheels.

My invention consists in providing for a lateral movement of the pivot for the lever, 20 preferably by pivoting the lever to a support or hanger which may slide, as hereinafter set forth.

In the drawings, Figure 1 is a plan of as 25 much of a car and brake attachment embodying my improvement as is needful to illustrate my invention. Fig. 2 is a section of car-frame, taken on line 1 1, Fig. 1, and shows a side view of parts of the brake mechanism.

Fig. 3 shows a plan view of the parts of Fig. 1 inverted.

30 The frame (composed of the longitudinal pieces *a*, transverse pieces *b*, *c*, and *d*) and the wheels *A*, having axles *f*, may be those of any car or car-truck. Each pair of brake-shoes *B* is fastened to a brake-beam, *C*, which 35 is hung to the frame of the car or car-truck by means of links *g* in the usual manner. At or near the center of each brake-beam *C* is connected a rod, *h*, which has a pivoted connection with a lever, *D*. Between the places

of connecting the rods *h* with the lever the latter is pivoted at *i* to a support or hanger, *E*. By means of the lever *D* the brake-beams may be simultaneously swung to cause the brake-shoes to press upon the wheels, rods *j* extending from the outer ends of the lever *D* 45 to the ordinary devices by which the power is applied. I fasten a socket, *F*, for each end of the support or hanger *E* to a transverse piece, *d*, so that the support or hanger may slide endwise, it being prevented from sliding 50 so far as to leave either socket, as by means of a screw, *k*, which passes through the socket and a slot in the support or hanger. Lateral motion of the pivot *i* being thus provided for, automatic adjustment of the lever will occur, 55 so that the brake-shoes will press upon all the wheels with equal force.

I am aware that the hanger for supporting the pivot of the lever *D* has been suspended by links whereby it may swing; but such construction I do not consider of such practical utility as that of my invention, since it is desirable that this hanger should be held as 60 stable as possible while providing for the lateral movement, as and for the purpose above 65 specified.

I claim as my invention—

In a car-brake, the combination of the lever *D*, connected with the brake-beams substantially as specified, a support or hanger, *E*, to 70 which said lever is pivoted, and sockets *F*, in which said support or brace may slide, substantially as and for the purpose set forth.

BELLVILLE L. RANDALL.
